UNITED STATES PATENT OFFICE.

WILLIAM H. BOLLAND, OF SAVANNAH, GEORGIA, ASSIGNOR OF ONE-FOURTH TO WILLIAM G. MORRELL, OF SAVANNAH, GEORGIA.

PORTABLE GRATE.

No. 927,214.

Specification of Letters Patent.

Patented July 6, 1909.

Application filed September 10, 1908. Serial No. 452,345.

To all whom it may concern:

Be it known that I, WILLIAM H. BOLLAND, a citizen of the United States, and a resident of Savannah, in the county of Chatham and

5 State of Georgia, have invented a new and Improved Portable Grate, of which the following is a full, clear, and exact description.

This invention is an improvement in fireplace grates of portable character, and has 10 in view a grate of the conventional or other design, hinged at one side to swing within and to the outside of the fireplace opening, in which latter position it is adapted to be lifted from its hinges and removed for emptying or 15 other purposes.

The invention further contemplates a reticulated or perforated cover for the grate, which is likewise mounted and serves for supporting articles to be heated; also an ash-pan, 20 and a handle interchangeable with the ash-pan and the grate.

Reference is to be had to the accompanying drawings forming a part of this specification, in which similar characters of reference 25 indicate corresponding parts in all the views.

Figure 1 is a perspective view of a fireplace having my improvements applied thereto; Fig. 2 is a perspective view of the 30 grate when removed from the fireplace; and Figs. 3 and 4 are respectively like views of the grate cover and the ash-pan.

The design of the grate 5 may be of any usual or other type, it only being necessary 35 that it be provided with a rear wall 6, which, in the present instance, is shown to be made up of a series of bars similar to the front wall. At one side near the front edge the grate is provided with integral perforated 40 ears arranged in vertical alinement, each forming a member of a hinge 7, the opposite members 8 of which are secured to the outer facing of the fireplace and have vertical pins adapted to engage in the apertures of the 45 hinge members carried on the grate, or, if desired the positions of the hinge members may be reversed. By thus mounting the grate it is adapted to swing within and to the outside of the fireplace opening, and when in this 50 last-named position can be vertically lifted from the hinges and removed for emptying

or other purposes, in this way dispensing with the necessity of first raking the ashes, cinders etc. into the ash-pan before the ashes can be removed.

55

A cover 9 of reticulated or perforated construction is supported in the same manner as the grate, as shown in Fig. 1, and not only serves to prevent the fire from popping out, but also as means for supporting vessels and 60 other articles to be heated. The especial construction of this cover I have shown consisting of a wire frame shaped to fit the fireplace above the grate and covered with a wire net. The hinge members of the cover 65 are carried by a vertically-arranged wire 10 rigid with one corner of the frame, the same being braced at adjacent sides by wires 11. When the cover is swung to an operative position within the fireplace opening it is prevented from sagging under the weight which 70 is placed on it at that end removed from the hinges, by a projection or bracket 12 attached to the side wall of the fireplace.

In completing the fireplace I make use of 75 an ash-pan 13 which is elevated and supported slightly above the hearth by brackets or angle-irons 14, adapting the pan to be easily slid to and from a position under the grate. In order that the grate and the pan may be 80 conveniently carried I provide both with perforations at opposite sides, in which an interchangeable handle 15 is adapted to be easily engaged and disengaged by springing its ends apart, as is obvious from Fig. 2. In this 85 manner one handle serves for both the grate and ash-pan and does not interfere with the use of either when the same are placed within the fireplace.

Having thus described my invention, I 90 claim as new and desire to secure by Letters Patent:

1. In a fireplace, a grate, a reticulated cover for the grate having an upright member secured at an outer corner thereof, bracing 95 wires extending from the upper portion of the member to the cover, hinged members arranged at an outer corner of the fireplace, and hinged members carried by said member, seating on the hinged members of the 100 fireplace and vertically displaceable therefrom.

2. The combination of a fireplace grate, and a cover for the grate, with both the cover and grate hinged at one side of the fireplace to permit them to swing into and out of the fireplace opening independently of each other or in unison.

In testimony whereof I have signed my

name to this specification, in the presence of two subscribing witnesses.

WILLIAM H. BOLLAND.
